ANTHONY COULAPIDES, OF BROOKLYN, NEW YORK

CIGARETTE CONTAINER

Application filed March 11, 1929. Serial No. 346,010.

This invention relates to dual packages for cigarettes. In dual or twin cigarette packages, the sheet material, usually thin cardboard, is formed to provide two packages or compartments hinged together so that the two compartments may be folded with their flat sides adjacent one another and make a compact attractive package to carry in the pocket.

10 The invention relates particularly to cigarette packages of this type in which the compartments are open at one end for the withdrawal of the cigarettes and are hinged together at these open ends, the portion of 15 the material forming the hinge also serving as the closure for the two compartments.

A container of this kind is disclosed in my copending application Serial No. 273,482 filed April 28, 1928, and the present invention relates more especially to improvements in the cigarette and cigar box shown in that application. My prior box meets admirably many of the requirements of a container of this nature. The primary object of the present invention, however, is to provide a dual cigarette container having still further improved manipulating features, ease of handling, accessibility of cigarettes, and in general a dual cigarette container which provides still greater convenience to the user.

Another object of the present invention is to so construct the box that it can be readily packed with cigarettes by automatic machinery.

Another object of my invention is to construct the dual cigarette package in such a way that when all of the cigarettes have been used from one compartment of the package 40 and this compartment discarded, the remaining compartment will give adequate protection to the cigarettes.

Another object of the invention is to provide a dual cigarette package of such construction that when a portion of the cigarettes are removed from either compartment, the remaining cigarettes are automatically held in position for easy removal.

The features of construction of my improved cigarette container will be understood

from the accompanying drawings taken in connection with the description following.

In these drawings:

Fig. 1 is a perspective view of the package in open position showing the facility 55 with which cigarettes may be removed therefrom.

Fig. 2 is a perspective view of the package in closed position.

Fig. 3 is a perspective view illustrating the 60 single package which is produced by removing one-half of the package shown in Figs. 1 and 2.

Fig. 4 is a perspective view showing the 65 interior arrangement of the package and the method of assembling.

Fig. 5 is a vertical section taken centrally of the package as viewed in Fig. 2.

Fig. 6 is a sectional detail of a partially 70 empty compartment.

Fig. 7 is a perspective view of the insert or cigarette retainer portion of the package.

Fig. 8 is a perspective view of one of the shells, and

Fig. 9 is a plan view of the insert or cigarette retainer.

Referring now to the accompanying drawings, my cigarette container consists of three parts, two similar shell portions 11, as shown in Fig. 8, and an insert portion 12, as shown 80 in Fig. 7, which forms a retainer or carrier for the cigarettes. After the insert portion has been folded in a manner to be presently described, with a group of cigarettes at each end thereof, a shell 11 is telescoped over each 85 end of the insert thus folded, and the double compartment cigarette container shown in Fig. 4 is thus produced.

As will also be described below, the two compartments of the container shown in 90 Fig. 4 may be folded as shown in Fig. 2 to bring the flat sides of the compartments adjacent one another. This is the normal folded position of the compartments for carrying in the pocket. When it is desired to open the package for removal of cigarettes, the two compartments are unfolded to the position shown in Fig. 4, the insert 12 is slid 95 part way out of one of the shells 11, and the opposite compartment bent downwardly as 100

illustrated in Fig. 1 so as to freely expose the layer of cigarettes in the upper compartment.

The insert (see Fig. 7) is cut out of an appropriate piece of cardboard or the like and is scored at certain predetermined places indicated by broken lines in the drawing to facilitate bending of the cardboard along these lines. A lighter scoring is made along 10 the longitudinal edges of the insert and across the protruding tabs 13. These tabs are then bent at right angles to the plane of the insert and perform the function of holding between them a single layer of cigarettes disposed in parallel relation and placed 15 upon the retainer so that the axes of the parallel cigarettes are parallel to the side of the insert. If desired the cigarettes may be placed at right angles to the side of the retainer. The end portion or apron 14 of the insert is then bent along the scored lines, each bend being at right angles so that one 20 of the aprons 14 lies above each group of parallel cigarettes which have been placed 25 upon the retainer 12.

When cigarettes have been placed on both ends of the retainer in this manner and partially surrounded by the tabs 13 and the apron 14, preferably having been previously 30 wrapped in foil or like moisture resistant material, the body or tubular shells 11 are slit over the folded portions of the retainer as shown in Fig. 4.

At the center of insert 12 and along the 35 edges thereof, two shoulders 15 protrude, and extending across the insert from the edges of one shoulder to the corresponding edges of the opposite shoulder and along the central line of the insert and the shoulders are three 40 lines of scoring. The outer two of these scoring lines perform the function of a hinge for the two compartments of the dual package so that when the shells 11 are in place the insert is bent normally along the two 45 scoring lines at the edges of the shoulders 15. The shoulders serve as a means of keeping the two shells 11 equally spaced from the center line of the insert 12.

Adjacent the shoulders 15 there are substantially 50 triangular cut-out portions 16. The interior extending apices of the triangular cut-out portions 16 are preferably joined by perforated weakened lines 17. However the mere fact that the triangular portions are 55 removed produces a weakened line at 17.

The weakened line 17 performs two functions. When one of the shells 11 is partially withdrawn (see Fig. 1), the supporting influence of the shell 11 is taken away from the 60 retainer 12 and the weakened line 17 permits the opposite compartment to fall out of alignment with the rest of the container, and exposing freely the ends of the cigarettes contained in this compartment. This weakened line 17 not only permits the opposite

compartment to fall out of alignment with the remainder of the container, but it promotes a hinging action.

The other function of the weakened line 17 is to permit the cardboard to be torn readily along this line when one compartment becomes empty, so that the empty compartment may be discarded. The remaining portion of the insert 12 serves as a closing flap to protect the cigarettes in the remaining compartment. This flap may be inserted between the inner wall of the shell 11 and the apron 14 of the retainer 12, if desired, but ordinarily will be allowed merely to fold against the outside of the compartment as this will give sufficient protection to the ends of the cigarettes.

When the remaining flap is used in this manner the retainer is bent along the central scored line so that the flap will lie flat against the shell 11 or fit within it. (See Fig. 3.) In case the tab is inserted, the edges of the vertical half of the projecting shoulders 15 may tend to restrict the entrance of the tab. This may be avoided by bending the vertical portion of the shoulders inwardly, and to facilitate the shoulders may be scored along the dotted lines 15'.

It has been found advantageous in packaging cigarettes to wrap them either in oil paper, tinfoil or the like, or possibly they may be wrapped in both tinfoil and oil paper in order to preserve them from the influence of the atmosphere. When cigarettes thus wrapped are packed in the dual package of the invention, an appropriate group of cigarettes is laid parallel to each other, and the sheet or sheets 18 of preserving wrapper is wrapped around the cigarettes in such a manner that the overlapping portions of the wrapping is just covered by the apron 14 of the retainer 12 as it is placed in position (see Fig. 4). When the ends of the wrapper 18 are covered in this manner by the apron 14, the shell 11 may be slid over the retainer 12 without injuring the delicate preserving wrapper around the cigarettes.

It is advantageous to have the ends of the preserving wrapper adjacent the protruding ends of the cigarettes, for when the package is opened and the shell 11 slid outwardly to expose the weakened line 17, the enclosing wrapper has to be withdrawn before the cigarettes themselves are exposed. This is easy to accomplish if the end of the wrapper is adjacent the end of the cigarettes and held just beneath the apron 14. This free end of the wrapper may, if desired, be then folded back into position after the required number of cigarettes are withdrawn from the package.

The withdrawal of cigarettes from the package permits the apron 14 to spring inwardly under the resilient action of the shell sides into the space between the tabs 13 from

which cigarettes have been drawn (see Fig. 6). Thus the apron 14 acts to hold the remaining cigarettes substantially in their parallel relationship (see Fig. 6). Due to this action of the apron 14, whenever the package is opened the ends of the cigarettes will protrude even though only a few cigarettes are left. This might, however, not be the case if there were no provision made for retaining the remaining cigarettes as nearly as possible in their original position in the compartments. Without this provision the last two or three cigarettes in the one side of the package are quite apt to fall sidewise, and their removal from the package is then very difficult.

The shells 11 are retained in their position surrounding the insert by frictional engagement of the inner surfaces of the shells exteriorly of the folded insert. When the two shells are placed around the folded and filled retainer they are pushed toward the center until the edges of the shells engage shoulders 15. Thus the two independent shells are automatically maintained in spaced relation to each other equi-distant from the center of the insert.

When the insert or retainer is folded at right angles along the two lines extending from the edge of one shoulder to the corresponding edge of the opposite shoulder, these two scored portions serve as hinges for the two compartments and also connect the two compartments. When thus folded the two compartments lie in parallel relationship adjacent each other (see Fig. 2). In this form the improved package of cigarettes occupies a minimum of space and is carried in the pocket conveniently.

The construction of my improved container is such that it can be readily packed or filled with cigarettes by automatic machinery. Referring to Fig. 9, sheets of foil or other protective wrapper are deposited upon the insert 12 on each side of the center line thereof. A layer containing for example 10 cigarettes is then deposited on top of each of these wrappers, and substantially simultaneously therewith the tabs 18 are folded upwardly and serve to hold the cigarettes in the spaces between them. Then the inner ends of the foil wrapper are folded over the tops of the inner ends of the cigarettes and the aprons 14 are folded over the outer ends 55 of the cigarettes, carrying the outer ends of the foil wrapping with them.

The insert or retainer 12 then contains both layers of cigarettes and is in the condition shown in the right hand portion of Fig. 4, ready to have the shells 11 telescoped thereupon. The shoulders 15 aid in this operation to secure the accurate centering of the shells upon the insert 12.

In order to make it possible for a container 65 of the type disclosed herein to compete with

soft wrapped or bundle wrapped packages, the item of cost is of most importance. The container of my invention, however, can be made for a comparatively low cost because it does not contain an inordinate amount of 70 material and furthermore because the multiplicity of layers of cardboard in the finished package, as shown in Fig. 5, renders possible the use of a light weight material; yet the cigarettes are protected adequately because 75 the multiplicity of layers produces in effect a laminated box having greater strength than can commonly be procured with the use of light weight material in packages or boxes of the ordinary construction. 80

Another feature of the improved box is the tightness of packing which can be used without damage to the cigarettes. The thickness of the shells can be made so as to slightly compress the cigarettes at their sides and the 85 width of the shells can be made so as to squeeze the cigarettes tightly, and yet because the structure of the box provides for drawing the whole layer of cigarettes partially out of the shell with the opposite cigarette compartment unfolded through an angle quite considerably greater than 180° as shown in Fig. 1, the ends of the cigarettes are exposed so freely that even though packed tightly they can be individually removed easily. The 90 tight packing has two advantages. First of all it produces a small compact package which takes up a minimum amount of room in the pocket, and secondly it reduces the amount of cardboard or other sheet material required for making the box. 95

The foregoing is to be considered merely as an exemplifying disclosure and the invention includes such modifications as come within the terms of the appended claims. 100

I claim:

1. A dual cigarette package comprising two separate bodies, and a folded retainer uniting said bodies and frictionally engaged therewith to form two cigarette compartments, folds in the connecting portion of the retainer to permit the compartments normally to lie with their sides adjacent one another, and the retainer having weakened lines located outwardly from the said folds to permit the compartments to be unfolded along one of said weakened lines through an angle substantially greater than 180° to freely expose the ends of the cigarettes. 110

2. A dual cigarette package comprising two independent compartments, and a folded retainer uniting the said compartments frictionally engaged with the inner surfaces thereof, portions of the said retainer being weakened by substantially triangular cut-outs extending toward each other from the opposite edges thereof to allow the retainer to be unfolded to freely expose the ends of the cigarettes and so that when the retainer is severed along one of the lines joining the 120

apices of the triangular cut-outs, the portion of the material adjacent the cut-outs forms a flap for closing the remaining compartment.

5 3. A dual cigarette package comprising a strip of sheet material folded to form a cigarette retainer, and a body slidable over each end to form a compartment for cigarettes, the intermediate portion of said strip joining the 10 two compartments being scored to permit the compartments to be folded with their flat sides adjacent one another, said strip having a weakened line spaced outwardly from each of said scorings and parallel thereto to permit 15 one of the compartments to be readily swung out of alignment with the opposite compartment by folding along one of said weakened lines when the cigarette retainer is slid partially out of the first mentioned compartment 20 so as to leave the ends of the cigarettes in said compartments freely exposed.

4. A dual cigarette package comprising two independent shells, a folded retainer uniting said shells, frictionally engaged with 25 the inner surfaces thereof, the retainer having weakened portions, said weakened portions located within the independent shells when said shells are in closed position and adapted to permit the backs of the independent shells to be folded toward each other when one of the shells is moved away from 30 the center of the retainer a sufficient distance to bring one of the said weakened portions beyond the supporting influence of the other shell, thus permitting cigarettes to be freely 35 exposed and easily withdrawn from the package.

5. A dual cigarette package comprising two independent shells and a folded retainer 40 for cigarettes uniting the shells frictionally engaged therewith to form two independent cigarette compartments, folds in the connecting portion of the retainer to permit the compartments normally to lie with their sides 45 adjacent one another, and shoulders on the connecting portion of the retainer to position the shells in centrally spaced relation to each other upon the retainer.

6. In a dual cigarette package a cigarette 50 retainer having two portions for receiving in the same plane each a single layer of cigarettes, tabs at the side of each portion folded upwardly to engage the sides of the cigarettes, an apron at each end of the retainer for 55 folding over the ends of the cigarettes, each end of the retainer having a tubular shell telescoped thereon, and the retainer being folded at the inner edges of the shells so as to permit the shells to lie normally with their sides adjacent one another.

7. In a dual cigarette package a retainer 60 for receiving two layers of cigarettes in the same plane at opposite ends thereof, the retainer having aprons at each end folded over each layer of cigarettes and having a shell

telescoped over each end to form a compartment for each cigarette layer, the cigarettes being removed through the inner open ends of said shells, the retainer being folded along the inner edges of the shells to permit the shells to lie with their sides adjacent one another with the portion of the retainer between said fold lines serving as the closure for the cigarette compartments, the said portion of the retainer being laterally extended from the sides thereof forming stops serving to center the shells upon the container.

8. A dual cigarette package comprising two independent compartments, a folded retainer uniting the said compartments frictionally engaged with the inner surfaces thereof, portions of said retainer being weakened by cutouts extending toward each other from the opposite edges thereof to allow the retainer to be unfolded to freely expose the ends of the cigarettes and so that when the retainer is severed along a line joining the said cutouts the portion of the material adjacent the cutouts forms a flap for closing the remaining compartment.

In testimony whereof I affix my signature.
ANTHONY COULAPIDES.
